DESIGN FOR A COMBINED SHRINE OR SIMILAR ARTICLE AND CASE THEREFOR

William Taylor Jones, Scranton, Pa., assignor to Consolidated Molded Products Corporation,
Scranton, Pa., a corporation of Delaware

Application March 19, 1946, Serial No. 127,666

Term of patent 14 years

(Cl. D29—23)

To all whom it may concern:

Be it known that I, William Taylor Jones, a citizen of the United States, residing at 440 S. Main Ave., Scranton, in the county of Lackawanna and State of Pennsylvania, have invented a certain new, original, and ornamental Design for a Combined Shrine or Similar Article and Case Therefor, of which the following is a specification, reference being had to the accompanying drawing, forming part thereof.

Figure 1 is an elevational view in open position of a case for a shrine embodying my new design and illustrating the inside of the case.

I claim:

The ornamental design for a combined shrine or similar article and case therefor, as shown.

WILLIAM TAYLOR JONES.
